UNITED STATES PATENT OFFICE.

EUGENE H. MCGEE, OF CHICAGO, ILLINOIS, ASSIGNOR OF ONE-THIRD TO LOUIS A. CORDA AND ONE-THIRD TO FRED T. BEERTSCHE, BOTH OF CHICAGO, ILLINOIS.

ELECTRIC-LIGHT SWITCH.

Application filed February 3, 1926. Serial No. 85,652.

This invention relates to electric light switches, and its principal object is to provide means whereby the intensity of light projected from one or more electric lamps 5 may be conveniently controlled and regulated. The invention has been designed especially for use in connection with the electric head lights of motor vehicles, but its use is not limited thereto. Another object of this invention is to provide a switch which may be located at any convenient place, for controlling the electric current of the lighting system, and containing a regulatable resistance element, whereby the head 10 lights may be caused to throw a powerful or intensely bright light, and they may be caused to throw a regulatable, dim light as is found necessary or desirable. Another object is to provide a switch, containing a 15 resistance element which will not become hot, whereby the switch may be placed on the steering wheel of a motor vehicle without any discomfort to the driver. Another object is to provide a non-heating resistance 20 element in an electric light switch which may be easily regulated to increase or decrease the resistance, whereby the intensity of the light projected from the head lights (when operating on the dim light circuit) 25 30 may be governed to suit the particular fancy of the driver. Other objects and advantages will appear in the course of this specification, and with all of said objects and advantages in view, this invention consists 35 in the several novel features hereinafter fully set forth and claimed.

The invention is clearly illustrated in the accompanying drawing, in which:

Fig. 1 is a plan of a fragment of the steering wheel of an automobile, equipped with an electric light switch embodying a simple form of the present invention; Fig. 2 is a vertical, cross section taken on the line 2—2 of Fig. 1; Fig. 3 is a central, horizontal section taken on the line 3—3 of Fig. 2; Fig. 4 is a central, vertical section taken on the line 4—4 of Fig. 3; Fig. 5 is a vertical, cross section taken on the line 5—5 of Fig. 3; Fig. 6 is a vertical section taken on the line 6—6 45 of Fig. 3; Fig. 7 is a vertical, cross section taken on the line 7—7 of Fig. 3; and Fig. 8 is a diagrammatic view of an electric head light current, of an automobile with my 50 switch included therein.

Referring to said drawing, which illustrates a simple embodiment of the present invention, the reference character 10 designates a fragment of the steering wheel of an automobile, and 11 the switch, forming the subject matter of this specification, secured to a spoke of said wheel, by a clamp 12. The switch may of course be placed at any readily accessible place adjacent the driver's station, and the steering wheel has been found to possess advantages, since the 60 driver's hands are practically always upon the wheel while driving the automobile, and the switch may be manipulated without taking the hand off the steering wheel.

The switch comprises, in the simple form 70 illustrated, a body 13 formed of non-conducting or insulating material, such as bakelite or fibre, which body is formed with a well or cavity 14 for containing powdered carbon 15, or other suitable powdered electric resistance material, which is interposed in and forms part of the light circuit. Contact making and breaking pieces are provided in the switch for passing the current around the resistance element 15, which 75 is done when it is desirable to have the head lights project a bright light. By properly manipulating the switch, the current can be passed through the resistance element or around it, as desired.

In the form of switch shown, the contact pieces comprise a stationary contact piece, such as a screw 16 threaded in an internally threaded hole 17 which extends lengthwise through the body 13. The other contact piece 18 is a movable one and as shown 85 comprises a screw, threaded in the tapped hole 17 and extending into it from the other end of the body. A knob or handle 19 is provided upon the protruding end of the screw 18 whereby it may be readily turned to bring the screw 18 into contact with the stationary contact piece 16 or withdraw it therefrom. A very slight movement of the handle 19 is sufficient to make or break contact between the contact pieces 16, 18. In 90 the drawing, the contact pieces are shown in contact; by moving the handle 19 in a counterclockwise direction, the contact is broken.

The electric connection between the contact pieces 16, 18 and other elements of the switch circuit will now be described. Secured in a groove or slot 20 in one end of

the body 13 is a metal plate 21, which for convenience, may be secured in place by a screw 22, the head of which bears against the plate 21, and the stem of which extends 5 through a hole, 23 formed in the body 13, and has a nut 24 on its other end bearing against the end of the body, opposite the one on which the plate 21 is secured. Extending into the well or cavity 14 from both 10 ends of the body, 13, and forming electrical contact with the powdered resistance element 15, therein, are two terminals or electrodes 25, 26, here shown in the form of screws threadedly secured in the cavity 14 15 which in this instance, is internally threaded near its ends for the reception of the screws 25, 26. The screw 26 extends through the metal plate 21, and the latter comprises a part of the dim light circuit, and part of the 20 bright light circuit, as will presently appear. Conductor wires 27, 28, lead from the screws 22, 25 and run to the main conductor b , of the light circuit. The screws 16, 25 are connected by a piece of wire 29 or otherwise 25 wise so as to establish electrical connection between them. The two circuits through the switch may be traced from the wire 27, through the screw 22, plate 21, contact screw 18, screw 16, wire 29, screw 25, and wire 28. 30 When contact between the screws 16, 18 is broken, the circuit through the switch may be traced from wire 27 through screw 22, plate 21, screw 18, plate 21, screw 26, resistance element 15, screw 25, and wire 28. 35 Cover plates 30, 31 are secured on the ends of the body 13 by screws 32 to furnish a finished appearance to the body, and one of said plates is formed with holes for the passage of the conductor cords 27, 28, and the 40 other with holes for the contact screw 18 and screw 26.

The switch may be installed as a permanent part of the original equipment of an automobile, or it may be quickly attached to automobiles unprovided with such a device. In the circuit illustrated in Fig. 8, the switch 11 is shown as installed in a bright light circuit of an automobile lighting system of conventional form. In this 45 lighting system wires, a , b run from light lamps A, A, through the switch, 11, on the steering wheel to the battery B. The usual lighting switch C, and resistance coil e, are interposed in the lighting circuit whereby 50 the circuit may be closed through the regular bright light circuit or the regular dim light circuit of the system, or entirely shut off. Ordinarily the wires b , b are joined at the point marked X, but when the present 55 switch is installed in the lighting system the wire b is cut at X and the wires 27, 28 of the dimming switch joined to the two ends b , b . The bright light circuit thereupon 60 passes through the dimming switch 11, 65 whereby the intensity of the head lights

may be controlled from a place on the steering wheel or other convenient and easily accessible place close to the driver's hands.

I have found that the intensity of the dim lights may be governed or controlled with the use of a powdered resistance element, such as powdered carbon, by rendering the carbon more or less compact. When left in a more or less loose state the resistance is made greater and the lamps are therefore caused to project a very dim light. When the resistance element is compacted more or less, the resistance becomes less and the lamps are thereby caused to project a brighter light. The degree of density of the powdered carbon may be governed by the screw 26. By turning up the screw 26 and thereby forcing it against the powdered carbon, the latter is compacted, and by turning the screw back the density is lowered. Some drivers prefer to drive with fairly bright driving lights, while others prefer to drive with very dim lights. The arrangement described furnishes means whereby the desired brilliancy of the lights (when dimmed) may be governed to suit the fancy of the driver.

The device is especially advantageous, because it can be placed in any convenient position, conveniently accessible to the driver at all times. This is an important factor 95 when driving at night on country roads or other dark places, because the bright lights can be quickly and readily dimmed when approaching another vehicle coming from the opposite direction, as is required by the laws of many States. Moreover the driver may control the lights without taking either hand off the steering wheel, which is a great 100 advantage. Furthermore, the switch does not become hot, as is the case with the use 105 of ordinary resistance coils, and for this reason it may be placed on the steering wheel or other convenient place adjacent the driver.

I claim as new and desire to secure by 110 Letters Patent:

1. In headlight dimming means for automobiles, a circuit controller, means for mounting said circuit controller on the steering wheel assembly of an automobile, said circuit controller having a body of non-conducting material, a stationary contact piece and a movable contact piece interposed in the electric circuit of the automobile headlights, the stationary contact piece being secured in said body, and the movable contact piece being threadedly secured in said body in alignment with said stationary contact piece and capable of being screwed up 115 against said stationary contact piece to close the circuit through said controller and arranged to be backed away from said contact piece to break the circuit, and a resistance element electrically connected with one of 120 said contact pieces.

2. In an electric light switch, a casing having an insulated well therein, a powdered carbon resistance element contained in said well, a stationary electrode at one end of said well in electrical contact with said resistance element, a screw, threadedly mounted in the other end of said well and in electrical contact with said resistance element, and forming an electrode therefor, a stationary contact member secured in said cas-
ing, a threaded contact making and breaking member, threadedly secured in said casing and arranged to make and break contact with said stationary contact member, said stationary and movable contact making and breaking members being electrically connected with said stationary and threaded electrodes for the resistance element. 15
